(57) **CLAIM**

The ornamental design for a water pipe, as shown and described.

DESCRIPTION

FIG. 1 is a top front perspective view of a water pipe showing my new design;

FIG. 2 is a front elevation view thereof;

FIG. 3 is a rear elevation view thereof;

FIG. 4 is a right elevation view thereof, with the left elevation view being a mirror image thereof;

FIG. 5 is a top plan view thereof; and,

FIG. 6 is a bottom plan view thereof.

The broken lines in the drawings depict portions of the water pipe that form no part of the claimed design. The oblique lines on the water pipe surfaces indicate that those surfaces are transparent.
